UNITED STATES PATENT OFFICE.

OBADIAH SHERWOOD, JR., OF EAST FAIRFIELD, VERMONT.

FIRE-ESCAPE LADDER.

SPECIFICATION forming part of Letters Patent No. 237,616, dated February 8, 1881.

Application filed November 27, 1880. (Model.)

To all whom it may concern:

Be it known that I, OBADIAH SHERWOOD, Jr., of East Fairfield, in the county of Franklin and State of Vermont, have invented certain new and useful Improvements in Extension Fire-Escape Ladders; and I do hereby declare that the following is a full, clear, and exact description of the invention, which will enable others skilled in the art to which it appertains to make and use the same, reference being had to the accompanying drawings, which form a part of this specification, and in which—

Figure 1 is a side view of my extension-ladder folded upon its truck, with all appurtenances complete. Fig. 2 is a plan or top view of the same. Fig. 3 is a perspective rear view of the ladder extended to its full height. Fig. 4 is a detail view of the brake attachment. Fig. 5 is a detail view of the lower part of one of the extension-sections, showing the self-operating safety-hook; and Fig. 6 is a detail view of the adjustable extension-prop with its grooved incline.

Similar letters of reference indicate corresponding parts in all the figures.

My invention contemplates certain improvements in portable extension-ladders or fire-escapes, having for its object to construct a ladder of this class which can be raised or lowered in a few moments and with little labor, which shall be strong and safe, and yet comparatively light in weight, and adapted for a short truck, so that it can readily turn corners and be used in narrow streets, where a long truck could not well be managed.

To this end my invention consists in the detailed construction and combination of parts of a truck, a turn-table, and extension-ladder composed of three or more sections, an adjustable extension-prop for supporting the lowermost ladder-section when raised in an upright position, a brake device for preventing motion of the truck when the ladder is in use, a safety-hook attachment to the several extensible ladder-sections, and mechanism for operating the extensible sections and their adjustable extension-prop, substantially as hereinafter fully described, and particularly pointed out in the claims.

In the annexed three sheets of drawings, A

is a truck-frame, made as light as is consistent with strength, and supported upon axles and wheels B B. This truck carries a turn-table, C, which may be adjusted at right angles to the truck, as shown in dotted lines in Fig. 3 of the drawings, or at any other desired angle thereto, and is held in any given position upon the truck by a lock-pin, a.

At the rear end of the turn-table C are two vertical uprights, b b, united by a cross-piece, e, which forms a prop or support for the grooved incline D, one side of which has a series of notches, d d, for the purpose hereinafter stated, while its outer or upper end is provided with a sheave or pulley, E, over which passes a rope, e, one end of which is attached to and wound by the windlass E', while the other end is secured in the lower end of the sliding extension-prop F, a short distance above a caster or small wheel, f, which runs in the grooved incline or way D and forms the foot of the prop.

g is a pawl, which engages with the notches d in way D, to prevent the prop from slipping back after it has been hoisted up by the windlass E' and rope e to the proper position. This prop or support consists of two parts—viz., a lower beam, F, having the caster or roller f and pawl g, and an upper part or section composed of two beams, F', which said upper part slides upon the lower section, and is operated by a rope, h, passing over a pulley in the upper end of the lower section, F, one end of the rope being connected to a strap or eyebolt in the lower end of the upper sliding part, while the other end is attached to a windlass, i, upon the lower end of section F. By turning this windlass and winding up the rope the prop F' may be extended to its full length and prevented from slipping back by a pawl, k, which engages with a ratchet-wheel on the windlass, as usual.

To the forward end of the turn-table C is hinged the lower ladder-section, G, one side of which has a laterally-projecting bracket, l, through which is inserted a screw, m, the lower end of which bears against the hinge-block n. By turning this screw the ladder may be adjusted laterally upon its turn-table, so as to stand in a perpendicular position at all times, when in use, without respect to the inclination

to one side or to the other of the truck and turn-table, caused by unevenness in the ground.

In the present illustration of my invention I have shown three ladder-sections, G G' G², the two upper ones of which are provided at their lower end with hinged safety hooks or catches H, the construction and operation of which will readily be understood by reference to the detail view, Fig. 5, of the drawings. Each of these hooks is composed of a shank, o, the lower end of which is pivoted in the side piece of the ladder, (one on each side,) while its upper end, which is inserted through a staple or keeper, p, to control its play, has a head, q, rounded on its upperside, and forming a projecting hook, r, at one end and a lip, s, at the end opposite. Above each of the hooks H is pivoted a stop, t, which may be turned down against lip s, so as to prevent the hook from turning. In extending the ladder these several stops t are turned up and out of the way, so as to give free play to the hooks, and as the ladder-sections are slid up one upon another, the rounded head q of each of the hooks, striking the rungs or steps of the section next behind, causes the hook to be tilted back out of the way, when it will immediately again fall back into position and hook onto the ladder rung or step just passed. Thus, if the tackle should break or slip while the ladder is being extended, the several sections could not slide back, but would be held in the positions to which they had been raised by their self-operating safety-hooks H. When the ladder has been extended to its full length, the hooks may be locked in place, to prevent accidental slipping out, by turning down the stops t.

Hinged to both sides of the lower ladder-section, G, is a bracket, I, having hinged braces K, the lower ends of which may be stepped into sockets u, provided a little lower down on each side of the ladder. Bracket I has eyes v, through which are inserted the stays or guy-ropes L L, and to the upper end of the intermediate ladder-section, G', are attached similar guy-ropes, M M, reaching down to the rear end of the turn-table, on opposite sides of which they are made fast.

To the forward end of the turn-table is hinged a short ladder, N, to facilitate reaching the foot of the main ladder in ascending, or the ground in descending; and this also serves, in connection with the hinged prop O at the rear end of the turn-table, to keep the truck steady on the ground and prevent rocking or swaying of the turn-table while the ladder is being operated and ascended.

After the lower or main ladder-section G has been raised in position the sliding sections G' G² are extended by ropes P P', operated by a windlass, Q, in a manner well understood, as that is common to all extension-ladders of this class; but prior to the hoisting and extending of the ladder the truck is fixed on the ground by a brake device consisting of the shoes R R, of which there is a pair for each of the hind

wheels, secured at the lower end of curved arms S S, the upper ends of which are pivoted a short distance above the hind axle on each side. The opposite pairs of curved arms are united by beams or bars T T, one for each side of the axle, so as to move in unison with each other, and upon one of these cross-bars is hinged a curved rod or circle-bar, U, having two offsets, w w', and a stop-pin, x. This curved bar is inserted through a staple or keeper, y, on the opposite cross-bar T, passing under the axle, so that the brake-shoes R R may be locked upon the wheels at their under side, close to the ground, by slipping the circle-bar U through staple y till the inner offset or shoulder, w, catches over bar T, thus keeping the two bars with their respective brake arms and shoes together. When it is desired to "let go" the brakes preparatory to moving the truck, the circle-bar is unshipped from bar T, with which it engages, and this bar is pushed up above the second offset, w', and held in place by a hook, z, which is hitched into a staple secured in the axle.

From the foregoing description, taken in connection with the drawings, the operation of my improved extension-ladder will readily be understood. To extend the ladder from the folded position shown in Figs. 1 and 2 to that represented in the perspective view, Fig. 3, the first step is to loosen the guy-ropes, (the upper ends of which may have hooks, so that they may be quickly fastened to their respective ladder-sections when required.) Next, the bracket I is raised and its braces K K stepped into their sockets. After this, (all the guy-ropes being cast loose,) turn the crank of windlass E', to draw the lower end of the extension-prop up the incline. Next, turn the crank of windlass i to extend the prop to its full length, care being taken to see that the pawl is down to hold the prop in position when extended. After this, turn up the stops or buttons t, that hold the safety-hooks H back and out of the way while the ladder is being folded, but allow them to operate as the sections are being extended one upon another. Next, turn the crank of the ladder-windlass Q until the ladder is extended to the proper height; and, finally, tighten the guy-ropes and fasten to the turn-table, as described. The guy-ropes may, however, be dispensed with when the ladder leans against and is supported by a wall or building, and are only required when the ladder is to be ascended standing alone and without support to brace its upper end.

A seventy-foot ladder composed of three sections, and constructed according to my description, may be operated and extended to its full length, ready for use, by one man within the space of one and one-half minute, or with two men this may be done in less than one minute.

In constructing very long ladders, gears may be used to operate the several windlasses and

cranks, for the purpose of economizing power and facilitating the operation of raising and extending the ladder.

Having thus described my invention, I claim 5 and desire to secure by Letters Patent of the United States—

1. The combination of the ladder-truck A B, adjustable turn-table C, having grooved and notched incline D, provided with the pulley 10 E, windlass E', and rope e, hinged extension-prop F F', having rope h and windlass i, and hinged ladder-section G, substantially as set forth.

2. In combination, the ladder-truck A B, turn-table C, hinged ladder-section G, having the hinged bracket I K K and sliding extension-sections G' G², safety-hooks H, with their stops t, and guy-ropes L L M M, substantially as and for the purpose herein shown and speci- 20 fied.

3. The combination, with the truck-wheels B B, of the brake mechanism or attachment, composed of two pairs of hinged arms, S S, having brake blocks or shoes R R, parallel 25 cross-bars T T, and hinged segmental bar U,

having offsets w w', constructed and combined substantially as and for the purpose shown and set forth.

4. The improved extension-ladder fire-escape herein shown and described, composed of the truck A B, with its brake attachment, turn-table C, provided at one end with the hinged ladder N, and at the opposite end with a hinged prop, O, grooved and slotted incline D, having pulley E, windlass E', and rope e, extension-prop F F', having windlass i, rope h, and roller f, hinged ladder-section G, having sliding extensions G' G², with their tackle P P' and windlass Q, and adjusting or balancing screw m, hinged bracket I K K, and guy-ropes or 30 stays L L M M, all constructed and combined substantially in the manner and for the purpose herein shown and set forth.

In testimony that I claim the foregoing as my own I have hereto affixed my signature 45 in presence of two witnesses.
